UNITED STATES PATENT OFFICE

LEON L. WHITE, OF TAMPA, FLORIDA

SANITARY NAPKIN

Application filed December 21, 1928. Serial No. 327,683.

This invention relates to apparel and more particularly to a device known as a sanitary napkin.

One object of the invention is to provide a sanitary napkin having a pad enclosed in a jacket consisting of a sheet of gauze fabric folded about the pad of absorbent material and having its end portions extending from the pad to provide front and rear tabs adapted to be connected with a waist-encircling belt so that the pad will be suspended in its proper position.

Another object of the invention is to so form the rear end portion of the sheet that, when folded, a pair of tabs will be formed at the rear of the napkin, which may extend upwardly in diverging relation to each other and thereby allow the napkin to be well supported and comfortable to wear.

Another object of the invention is to provide tabs consisting of a plurality of layers of fabric so that they will be very strong and not liable to tear loose when pinned to companion tabs of a waist-encircling belt.

Another object of the invention is to so form the two rear tabs of the napkin that they will lie flat without a tendency to roll up or wrinkle and also to eliminate any unequal or bias strain on the fabric where the tabs join the main body portion of the napkin.

The invention is illustrated in the accompanying drawing, wherein:

Figure 1 is a top plan view of the improved napkin.

Figure 2 is a view of the blank or sheet from which the pad encasing jacket is formed.

Figure 3 is a transverse sectional view taken through the pad and jacket along the line 3-3 of Figure 1.

Figure 4 is a transverse sectional view taken on the line 4-4 of Figure 1.

The improved sanitary napkin constituting the subject matter of this invention includes a pad 1 which is preferably formed of absorbent cotton although any absorbent material may be used. This pad may be of any size desired and it is encased in a jacket 2 having an intermediate pad enveloping por-

tion 3 and end portions which project beyond the ends of the pad and form rear and front suspending tabs 4 and 5. It should be noted that the front tab 4 extends the full width of the pad whereas the rear tabs are each half the width of the pad and extend in diverging relation to each other, as shown in Figure 1 of the drawing, so that they diverge upwardly when the napkin is in use. By this arrangement there will be no uncomfortable roll of gauze in the body crease and the napkin may be very well supported from the waist-encircling belt and will be comfortable to wear and yield to the body postures and movement of the wearer.

The jacket in which the pad is enveloped consists of a rectangular sheet of porous fabric such as gauze used for bandages. This sheet, which is shown in Figure 2 and indicated in general by the numeral 6, is slit longitudinally from one end for a portion of its length, as shown at 7, and is also provided with transversely extending slits 8 leading from opposite side edges in alignment with the inner end of the slit 7 and terminating intermediate the side edges of the sheet and inner end of the slit 7.

In view of the fact that the sheet is rectangular in shape and preferably oblong, it may be cut from a strip of gauze without waste of material.

When forming the napkin, the sheet 6 is placed flat upon a table or other support and a pad disposed upon the sheet with one end close to the inner end of the slit 7. The side portions of the sheet are folded along the dotted lines 9, as shown at 10, in Figures 3 and 4, to eliminate raw edges which are liable to ravel. It is to be understood that if the sheet is cut from a strip having a width corresponding to the distance between the dotted lines 9 it will be formed with a selvage edge at both sides, in which case folding will not be necessary. After the marginal portions of the sheet or blank 6 have been folded along the lines 9, the sheet is then folded along the dotted lines 11 in spaced relations to opposite sides of the center slit 7 to provide portions 12 and 13 disposed one in overlapped relation to the

other and serving to cover the pad as shown in Figure 3. The loose corner of the overlapped portion 13 is tacked by stitches to retain it in position. Therefore, the sheet will be disposed in enveloping relation to the pad with an end portion extending from one end of the pad to form the suspending flap or tab 4 of the same width as the pad. The other end portion of the sheet also projects from the pad and constitutes tongues 14 which are folded longitudinally together with the body portion of the sheet along the line 11 and the transverse slits 8 form the tongues 14 with side extensions or wings 15 which are folded along the dotted lines 16 to extend through the slit 7 and flat against the under surfaces of the folded tongues, as shown in Figure 4. It will thus be seen that each of the tabs 5 will consist of three thicknesses of fabric and there will be no danger of the tab tearing loose from a pin or buckle by means of which each tab is to be connected with the cooperating tab of a waist-encircling belt. This formation provides a napkin which can be very easily applied and firmly secured and further provides a napkin which is free from wrinkles and not liable to be torn or otherwise damaged by strain. When the napkin is worn the side having a single thickness of gauze and constituting the lower portion of Figure 3, is disposed uppermost so that it fits against the person of the wearer and when so worn the flaps 15 of the tabs 5 will be uppermost against the wearer and remain in their proper positions without being sewn or otherwise fastened.

Having thus described the invention, what is claimed is:

- 40 1. A napkin comprising a pad of absorbent material, and a jacket for said pad, the said jacket consisting of a sheet of soft porous fabric split longitudinally from one end for a portion of its length and split 45 from opposite sides for a portion of its width along a line adjacent the inner end of the longitudinally extending slit to form end tongues having side flaps of one end portion of said sheet, the body portion of the sheet and the said tongues having side portions folded inwardly to eliminate raw edges, and the sheet being folded longitudinally in spaced relation to opposite sides of the longitudinally extending slit to form a tubular portion enclosing said pad and extending beyond one end of the pad to form a suspending tab corresponding in width to the pad, the said flaps being folded through the longitudinally extending slit and disposed against the tongues and together therewith forming flat suspending arms having smooth side edges and adapted to extend upwardly in diverging relation to each other.
- 60 65 2. A napkin comprising a pad of absorbent material, and a jacket for said pad con-

sisting of a sheet of soft porous fabric folded longitudinally to enclose the pad and having end portions projecting from opposite ends of the pad, one end portion of the jacket forming a suspending portion of the 70 same width as the pad and the other end portion of the sheet being slit longitudinally intermediate its width and from opposite sides before the sheet is folded to provide tongues having side flaps, the tongues being 75 folded longitudinally and the flaps folded about the same to form flat suspending tabs having smooth side edges.

In testimony whereof I affix my signature.
